IRONING BOARD

Viggo Rasmussen, Minneapolis, Minn.

Application March 17, 1943, Serial No. 479,403

3 Claims. (Cl. 38—126)

This invention relates to an ironing board and particularly to an ironing board having comparatively small dimensions so that it may be conveniently transported in the user's luggage or stored in quite a small space. Said board is also preferably equipped with simple and efficient means for supporting it upon a door knob so that it is firmly supported in position, said board having means to abut the door on which said knob is carried.

It is an object of this invention to provide an ironing board of comparatively small size having a rigid bail handle pivoted to the top thereof of adjacent one end, said handle being adapted to be disposed over the top of a door knob and engage said knob so as to prevent lateral movement of said board, said board having means to abut a door below said knob and adjacent the same together with other means to abut said door some distance below said first mentioned means.

It is a further object of the invention to provide an ironing board preferably of comparatively small size having means secured to its top side for engaging over a door knob and holding said board firmly in position, said board having portions to abut the door closely below said knob, said board having articulated means at its underside adapted to extend along and lie closely against said board when the board is not in use and being constructed and arranged to be brought into position to engage said board and door for forming additional supporting means therefor.

It is more specifically an object of the invention to provide an ironing board preferably of comparatively small size having means for supporting it upon a door knob, said board having a slot intermediate its ends at its underside extending transversely thereof, a clip secured in said slot having substantially parallel sides extending longitudinally of said board, an arm pivotally secured adjacent one end of said board, a second arm pivoted to said arm and having a bevelled end adapted to engage in said slot, said first mentioned arm and said end of said board having yielding means adapted to engage a door with said bevelled end engaged in said slot, said first mentioned arm being adapted to fit snugly in said clip to hold said arms in inoperative position.

These and other objects and advantages of the invention will be fully set forth in the following description made in connection with the accompanying drawing in which like reference char-

acters refer to similar parts throughout the several views and in which:

Fig. 1 is a perspective view showing a portion of a door and door frame with the ironing board of this invention supported upon a door knob on said door;

Fig. 2 is a view in side elevation of the board in a position to be packed or stored, a small portion being broken away;

Fig. 3 is a partial plan of one end of said board;

Fig. 4 is a partial vertical section taken on line 4—4 of Fig. 2;

Fig. 5 is a partial view partly in side elevation and partly in central vertical section showing the board supported upon a door knob and door; and

Fig. 6 is a partial section taken substantially on line 6—6 of Fig. 2.

Referring to the drawing an ironing board 10 is shown and while this could be of various sizes, it preferably is made of comparatively small size, the same tapering toward one end, which end is rounded. At its wider end said board is formed with spaced portions or lugs 10a and these are preferably covered or equipped with pads 11 of some soft or yielding material such as felt or rubber. A pair of small angular clips 12 are secured to the top of said board adjacent its wider end, said clips being oppositely disposed and having upstanding portions which are respectively parallel. Similar but slightly larger clips 13 are disposed at the underside of board 10 having portions vertically aligned with clips 12 and headed and nutted bolts 14 extend through the portions of clips 12 and 13 engaging said board and thus hold said clips firmly in position. Bolts 14 have flat rounded heads at the top of board 10 while the nuts thereon are disposed at the underside of said board. A rigid bail handle 15 preferably made of metal and of substantially semi-circular form, has its ends pivotally connected by the headed rivets 16 between the upstanding portions of clips 12. An arm 17 has one end pivoted by a rivet 18 between the depending portions of clips 13 and while this arm could be variously formed, in the embodiment of the invention illustrated it is shown as rectangular in transverse cross section. Arm 17 is bifurcated at its other end and the rabbeted end 19a of an arm 19 is disposed between the bifurcations of arm 17 and pivotally connected thereto by a headed and nutted bolt 20. Arm 19 has a beveled terminal end 19b. Board 10 between its ends and quite some distance from its wider end has formed therein at its underside a slot 10b.

A U-shaped clip 22 preferably of metal, is secured in slot 10b against the bottom thereof by a screw 23. It will be seen that the sides of clip 22 depend in substantially parallel relation and are disposed to extend longitudinally of board 10. Arm 17 has a pad 24 of some soft or yielding material such as felt or rubber, secured adjacent its bifurcated end.

In operation, when the board is to be stored or transported with luggage, it will be brought to the position shown in Fig. 2, except that the handle 15 will be swung down against the top of the board. With the board in this collapsed position arm 17 fits snugly between the sides of clip 22 and is frictionally held therein. Arm 19 can thus extend longitudinally in contact with the underside of the board. The board in this collapsed position occupies small space. When the board is to be used, the arm 17 is released and the bevelled end 19b is disposed in the slot 10b with the surface of the bevelled portion engaging one side of said slot. This brings the arms 17 and 19 into the position shown in Fig. 5. The handle 15 can now be engaged with or placed over the top of the door knob 26 of door 27 with said bail handle disposed in the rear of the large handle end or portion of said knob and said handle and the board will be supported upon said knob 26. The pads 11 will now swing against and abut the side of the door as shown in Fig. 1. Pad 24 will also be disposed against and abut the side of the door. The handle 15 takes an inclined position as shown in Fig. 5 and due to its semi-circular shape it engages the sides of the handle portion knob 26 and locks firmly against said portion so that no lateral movement of the board is possible. The board is thus very firmly held in its supported position and extends laterally in a substantially horizontal plane. It is obvious that the board can be readily released from knob 26 and quickly brought to its collapsed position.

From the above description it will be seen that I have provided a very simple ironing board structure and one which can easily and quickly be supported upon the knob of a door. The board can thus be used by people in hotel or other guest rooms and can be easily and quickly used by girls or other people who live in rented rooms. Obviously the board will also be handy for the housewife. It has been previously proposed to have a flexible handle extending over a door knob, but with such a construction the end of the board adjacent the knob could swing laterally. This was objectionable and it is not convenient to do ironing on such a board. As stated, with the present construction and the rigid handle 15, said handle extends forward and in effect locks against the side of the handle portion of knob so that no lateral movement of the handle or board is possible. The board is thus very firmly and solidly held in position. This is a new and important function and result. As stated, the handle 15 can be swung down in engagement with the top of the board when the same is in collapsed position. The parts of the structure are all quite simple and can be made from easily procured materials and at small expense. The device has been amply demonstrated in actual practice and found to be very successful and efficient.

It will of course, be understood that various

changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. An ironing board having in combination, an elongated board, a rigid bail handle of arcuate form pivoted to the top of said board adjacent one end constructed and arranged to engage over the shank of a door knob and extend forwardly to engage the sides of the handle portion of said knob, said end having lateral spaced portions, yielding means on said portions adapted to abut said door slightly below and at each side of said knob, an arm pivoted at one end to said board at its underside adjacent said end, a second arm pivoted to the opposite end of said arm and having a free beveled end, said board having a slot in its underside some distance from said end against one side of which said beveled end is adapted to seat and yielding means on said first mentioned arm adapted to abut said door some distance below and aligned centrally vertically with said end of said board when said beveled end is so engaged for supporting said board.

2. An ironing board having in combination, an elongated board, a bail handle pivoted to the top of said board adjacent one end of the same constructed and arranged to engage over the shank of a door knob and extend forwardly to engage the sides of the handle portion of said knob, said board having a slot extending transversely in its underside some distance from said end, a U-shaped clip secured in said slot having flat sides extending longitudinally of said board, an arm pivoted at one end to the underside of said board adjacent said end, a second arm pivoted to said arm at the opposite end thereof and having a beveled end adapted to be disposed in said slot between the sides of said clip with said bevelled portion engaging one side of said slot, said arms being constructed and arranged to extend longitudinally along the underside of said board substantially in contact therewith, said first mentioned arm fitting snugly between the sides of said clip to hold said arms in said position.

3. An ironing board having in combination, an elongated board, a rigid bail handle of arcuate form pivoted to the top of said board adjacent one end and substantially centrally transversely thereof constructed and arranged to be disposed over a doorknob in the rear of the handle portion thereof to support said board, said bail handle being constructed and arranged to extend forwardly so that the sides of said handle engage the said handle portion to prevent lateral movement of said board, said board having means at said end to abut said door below said knob at both sides of said knob, an articulated bracket movable to position to engage said board between its ends and at its underside, and to extend to and abut said door some distance below said end of said board for further supporting said board, thus giving a three point abutment, said bracket being movable to collapsed position along and adjacent the underside of said board.

VIGGO RASMUSSEN.
